UNITED STATES PATENT OFFICE

CARL T. PENTON, OF BUFFALO, NEW YORK.

THERMOSTATIC SWITCH.

Application filed December 6, 1923. Serial No. 378,840.

This invention relates to improvements in thermostatic switches, proposing a switch which is available for the automatic control, according to temperature variations, of electrical appliances or apparatus, such as ovens, water heaters and the like, where it is desirable that the temperature be maintained at a certain approximate degree or within a certain range.

10 The principal objects of the invention are to secure a quick make and break of the co-operating electric contacts whereby destructive arcing is eliminated and to provide for this purpose mechanism of simple structural character which will be at all times certain and reliable and will not be liable to derangement.

A further object is to promote facility in the fitting and removal of the operating parts 20 relatively to the structure with which the thermostat is associated by providing for the assembly of such parts as a self contained unit through which the circuit to be controlled is completed.

25 A further object is to provide facility in regulating the degree of temperature at which the circuit will be opened and below which it will be closed.

With the above objects in view the invention consists generally in certain novel features of structure and combination which will be pointed out in detail as the description proceeds and which involve the provision of friction means for retarding the action of the 35 thermostatic spring, provision for the removable mounting of the operating parts as a self contained conducting unit, and provision for the regulation of the critical temperature degree or range by the movement of an indicating part and without the necessity of any manipulation or adjustment of the co-operating contacts.

An embodiment of the invention is illustrated in the accompanying drawing wherein: 45 Figure 1 is a longitudinal sectional view of the switch.

Figure 2 is a front elevation thereof.

Figures 3 and 4 are sectional views on the lines 3—3 and 4—4 of Figure 1.

50 Figure 5 is a sectional view on the line 5—5 of Figure 3.

Figure 6 is a sectional view on the line 6—6 of Figure 1.

The switch is supported by the wall A of 55 the electrical appliance to be controlled, such for example as a water heater, and is subject

to the heat developed within the chamber of such appliance. The casing in which the operating mechanism is enclosed is preferably made in two parts, namely the casing 60 proper as 1 and a sleeve-like extension thereof as 2. The extension 2 is conveniently used for the support of the switch and for this purpose has threaded engagement in the wall A, a portion of the extension 2 projecting into 65 the chamber provided by said wall.

The casing 1 and extension 2 are preferably made as separate parts, the casing having a collar 3 projecting from its rear wall and fitting over the front end of the extension upon 70 which it is secured by a screw 4. In order to provide access to the operating parts the front wall 5 of the casing is removably secured, as by screws 6, to the body of the casing. 75

The support for the operating parts consists of a metallic frame 7 which is secured by fastening bolts 8 and 9 to the rear wall of the casing 1. The bolts 8 and 9 are provided on their projecting rear ends with securing nuts 80 10 and are available as binding posts for the connection of the terminals 12 of the wires which are joined to the terminals of the heating element or other electrical receiving device. The frame 7 is insulated from the casing 85 1 by a plate 13 of suitable insulating material which is fitted between said frame and the rear wall of said casing and is supported by the bolts 8 and 9. The bolt 8 is in electrical contact with the frame 7 and is insulated from 90 the casing 1; the bolt 9 is insulated both from the frame and from the casing.

Any suitable make-and-break device may be employed, that shown being preferred and consisting of a laterally arranged stationary 95 contact 14 connected to the bolt 9 and co-operating with a contact 15 provided on a movable bar 16. The frame 7 is provided along its upper side with a pair of spaced lugs 17 and 18 whereof the lug 17 carries the 100 contact 14 (from which it is suitably insulated) and the lug 18 serves for the attachment, as by a screw 19, of an indicating scale 20 which bridges said lugs and co-operates with an indicating finger 21, the scale 20 and finger 21 being visible through a window 22 in the front wall 5.

The bar 16 is operated by a thermostatic spring 23, as shown a helically wound spring, and projects radially from a head 24 mounted fast at one end of a longitudinal sleeve 25 which functions as a shaft and is mounted

upon a longitudinal bar 26. The bar 26 is supported for turning adjustment with reference to its axial center in a thimble 27 provided at the lower side of the frame 7 and, 5 together with the sleeve 25, projects into the extension 2. The bar 26 is provided at its rear end with a head 28 and the spring 23 which is located in the extension 2 beyond the sleeve 25 is secured at its ends to said sleeve 10 and said head. The bar 26 is held against displacement under the pressure of the spring 23 by a nut 29 which is fitted at the front end of the bar upon a threaded portion 30 and is backed by a suitable cushioning washer 31, 15 in turn backed by the thimble 27.

The thimble 27 also provides a bearing for an adjusting disc 32 which is mounted behind said thimble upon the bar 26 to which it is made fast in any suitable manner and which 20 carries the finger 21. The disc 32 is pressed against the rear face of the thimble 27 by the head 24 (under the pressure of the spring 23) and may be turned by the finger 21 in either direction to effect a corresponding movement 25 of the rod 26 and a consequent regulation of the tension of the spring 23. A friction disc 33, preferably composed of vulcanized fiber is fitted on the rod 26 between the head 24 and the disc 32, the friction disc being backed 30 by the adjusting disc and having a flat and wide contact with the adjacent face of the head 24 which is pressed against the friction disc by the spring 23.

The extension 2 is preferably closed at its 35 rear end by a head 34 and the spring 23 is arranged in the portion of the extension which projects into the chamber provided by the wall A where it is sensitively responsive to temperature variations in said chamber. Below a determined degree or range of temperature the spring 23, acting on the sleeve 25, and through it on the bar 16 will cause the contact 15 to engage the stationary contact 14. Above such degree or range of temperature 40 the spring 23 similarly causes the contact 15 to disengage the contact 14. The degree or range of temperature to be maintained is determined by the position of the finger 21 with reference to the scale 20, the movement of said finger along said scale being effective, through the rod 26, to regulate the tension of the spring whereby if the tension be decreased the spring will disengage the contacts 15 and 14 at a lower temperature 45 and if the tension be increased the spring will disengage such contacts at a higher temperature. The finger 21 is adjusted manually along the scale 20, the cover 5 first being removed as is obvious.

50 The movement of the bar 16 to effect the engagement or disengagement of the contact 15 relatively to the contact 14 is quick and in the nature of a snap action whereby destructive arcing, which might otherwise be 55 due to the high tension currents employed, is

avoided. This snap action of the bar 16 is secured by the provision of the friction disc 33 which, engaging the head 24, acts as a brake on the sleeve 25 in opposition to the spring 23. It follows that before the spring 70 23 can produce a movement of the bar 16 it must store sufficient power to overcome the braking effect of the disc 33 with the result that the bar 16 can have no gradual movement but is moved quickly or snapped in 75 either direction accordingly as it is being operated to engage or disengage the contacts 15 and 14.

The operating parts are assembled to constitute a self contained conducting unit which 80 may be removed from and inserted into the casing 1 and its extension 2. The circuit of the heating element or other electrical receiving device is closed through the terminal 9, contacts 14 and 15, bar 16, sleeve 25, rod 26, 85 disc 32, frame 7 and terminal 8. The frame 7 is the support for the operating unit and such unit is removed by first removing the front wall 5 of the casing 1 and then disconnecting the bolts 8 and 9. If desired the casing 1 and the operating unit may be removed together from the extension 2 after first backing off the screw 4.

Having fully described my invention, I 90 claim:

1. In a thermostatic switch, the combination of a movable contact part, a thermostatic spring for operating the same, an adjustable rod for regulating the tension of said spring, an indicating scale and co-operating finger constituting companion relatively movable elements, and operative connections between one of said elements and said rod whereby a movement of said element relatively to its companion element effects an adjustment of 100 said rod.

2. In a thermostatic switch, the combination of a movable contact part, a thermostatic spring for operating the same, means including an adjustable rod for regulating the tension of said spring, an indicating scale and co-operating finger constituting companion relatively movable elements, operative connections between one of said elements and said rod whereby a movement of said element 110 relatively to its companion element effects an adjustment of said rod, and means acting with braking effect to oppose the action of said spring whereby the latter must store power to a certain degree in order to operate 115 said contact part.

3. In a thermostatic switch, the combination of a supporting part provided with a thimble, a rod mounted in and projecting from said thimble, a sleeve mounted on and supported by said rod, a thermostatic spring connected at its ends to said rod and sleeve, the rod being adjustable whereby to regulate the tension of said spring, and a movable contact part actuated by said sleeve. 125 130

4. In a thermostatic switch, the combination of a supporting part provided with a thimble, a rod mounted in and projecting from said thimble, a sleeve mounted on and supported by said rod, a thermostatic spring connected at its ends to said rod and sleeve, a movable contact part actuated by said sleeve, and means acting with braking effect to oppose the action of said spring whereby the latter must store power to a certain degree in order to operate said contact part.

5. In a thermostatic switch, the combination of a supporting part provided with a thimble, a rod mounted in and projecting from said thimble, a sleeve mounted on and supported by said rod, a thermostatic spring connected at its ends to said rod and sleeve, the rod being capable of adjustable movement, an indicating finger connected to said rod for adjustably moving the same, a scale with which said finger co-operates, and a movable contact part actuated by said sleeve.

6. In a thermostatic switch, the combination of a supporting part provided with a thimble, a rod mounted in and projecting from said thimble, a sleeve mounted on and supported by said rod and provided with a head, a movable contact part operated by said sleeve, a thermostatic spring connected at its ends to said rod and sleeve, and a friction disc fitted upon said rod and pressed against said head with braking effect.

7. In a thermostatic switch, the combination of a supporting part provided with a

thimble, a rod mounted in and projecting from said thimble, a sleeve mounted on and supported by said rod, a thermostatic spring connected at its ends to said rod and sleeve, the rod being capable of adjustable movement, a finger connected to said rod and by which said rod may be adjusted, said sleeve being provided with a head, a friction disc fitted upon said rod, and engaging said head with braking effect, and a movable contact part actuated by said sleeve.

8. In a thermostatic switch, the combination of a movable contact part, a thermostatic spring for operating the same, means for regulating the tension of said spring, and a frictional connection between said movable contact part and a relatively stationary part, said connection acting with braking effect to oppose the action of said spring whereby the latter must store power to a certain degree in order to operate said contact part.

9. In a thermostatic switch, the combination of a movable contact part, a thermostatic spring for operating the same, an indicating scale having a movable element, means actuated by said element for regulating the tension of said spring, and means acting with braking effect to oppose the action of said spring whereby the latter must store power to a certain degree in order to operate said contact part.

In testimony whereof I affix my signature.

CARL T. PENTON.
